INVENTOR

Joseph S. Wood,

UNITED STATES PATENT OFFICE.

JOSEPH S. WOOD, OF BROOKLYN, NEW YORK.

GAS APPARATUS.

SPECIFICATION forming part of Letters Patent No. 228,848, dated June 15, 1880.

Application filed December 4, 1879.

To all whom it may concern:

Be it known that I, JOSEPH S. WOOD, of the city of Brooklyn, county of Kings, and State of New York, have invented certain Gas Apparatus, of which the following is a specification.

This invention relates to automatic apparatus for making gas from light hydrocarbons by means of heat; and its general object is to 10 simplify such apparatus and to perfect the automatic control of the operation.

The present invention consists, first, in a novel combination of parts for actuating the needle-valve of the retort, the cut-off or air 15 valve, and the gas cock or valve in the burner-supply pipe simultaneously at will; secondly, in a novel combination of parts for actuating said valves by a connection with the gas-holder drum to automatically regulate the operation. 20 according to the gas consumed; thirdly, in a novel combination of parts for closing all said valves instantaneously upon the fall of the gas-holder drum below a given point; fourthly, in the general combination of parts, whereby the 25 operation is automatically controlled, as aforesaid.

In the accompanying drawings, Figure 1 represents a vertical longitudinal section of my improved gas apparatus, and Fig. 2 a horizontal section of the same on line xx , Fig. 1.

In the drawings, B represents a gas retort or generator, of cylindrical or other shape, which is heated by a suitable burner, C, below the same, said burner being attached to the 35 bottom of the retort and surrounded by a perforated flange, D, which is cast in one piece with the bottom of the retort, and intended to retain the heat and protect the flame against accidental extinction by drafts. The naphtha or 40 other light hydrocarbon is conducted through a pipe, I, from the oil-tank to the retort B, while a gas-pipe, r, connects the burner C with a gas-holder, R, the supply of gas to the burner being regulated by a valve, f.

45 Cast in one piece with the retort B, or otherwise connected with the same, is a cylindrical barrel, F, which is arranged horizontally on the retort and adapted to guide the needle-valve H. The retort communicates by an opening 50 in its top part with the cylinder F of the needle-valve H, said cylinder being provided at

one end with a stuffing-box for the valve-stem and at the opposite end with a tapering orifice, o', for the conical end of the needle-valve.

The vapors generated in the retort pass 55 through the cylinder of the needle-valve and the discharge-orifice of the same into a mixing-chamber, A, which is arranged in line with the needle-valve and provided with an air-port, M, and an injection-throat, L. The vapors are 60 mixed in the chamber A with atmospheric air, so as to form illuminating-gas, which gas is forced through the injection-throat L and a connecting gas-pipe, O, into the gas-holder R. The communicating gas-pipe O is provided 65 with a cock, N, which serves to retain the gas in the gas-holder when it is desired to start the apparatus. The burner-supply pipe r is also provided with a cock, f', so that the supply of gas to the burner may be interrupted or 70 controlled.

The gas-holder R is constructed in the customary manner, with condensing-chambers S in the lower part and a vertically-guided drum in the upper part. The condensing-chambers S are divided by a partition, I, which, however, does not extend to the bottom of the condensing-chambers, so as to form an opening, which is sealed by the water in the condensing-chambers. Gas inlet and outlet 80 pipes T T' extend from the condensing-chambers upward into the gas-holder and terminate above the level of the water in the same.

The gas passes from the inlet-opening g' of the pipe O, through one condensing-chamber 85 S and pipe T, into the gas-holder, and through the outlet-pipe T' into the other condensing-chamber S, then through the service-pipe U to the building. The condensed vapors are collected in the first condensing-chamber and in 90 the gas-holder, and conducted in one case through the opening between the condensing-chambers and in the other case through the shorter outlet-pipe T' to the second condensing-chamber, and finally through the service-pipe U, which is arranged above the opening of the partition I, to a suitable collecting-trap, 95 from which the condensation is removed from time to time.

The drum of the gas-holder R is guided by 100 vertical rods b' in fixed exterior guide-brackets of the gas-holder. To the upper part of

one of the guide-rods *b'* is pivoted a bent slip-rod, *c'*, which is pressed by a spring, *d'*, against the recessed guide-bracket. A shorter release-rod, *e'*, of the slip-rod *c'* is arranged with an 5 eye, so as to be connected to a bolt, *q*, or other device of a lever, *E*, which is fulcrumed to a supporting bracket-arm, *G*, of the vapor-cylinder *F*. A spring, *J*, tends to press the lever *E* in upward direction. The opposite end of 10 the lever *E*, back of its fulcrum, is curved downward and connected pivotally to the outer end of the needle-valve. The front part of the lever is furthermore connected by lever-rods with a cut-off device for the air-port of 15 the mixing-chamber and with a lever-arm on the cock of the burner-supply pipe. The gradual filling of the gas-holder by the gas generated in the apparatus raises the drum and thereby the regulating-lever, which latter operates simultaneously the needle-valve, the 20 air cut-off, and the gas-cock of the burner-supply tube, so as to diminish more and more the generation of gas, but never interrupt it entirely. When, however, the gas in the gas-holder 25 is gradually consumed, the drum is lowered, the lever is moved downward, and the vapor-orifice of the valve-cylinder, the air-port of the mixing-chamber, and the cock of the burner-supply pipe are opened at the same 30 time, so as to increase the generation of gas. The gas apparatus is thus regulated automatically by the rise and fall of the gas-holder and by the consumption of gas.

In case the heating-flame of the burners should 35 accidentally be extinguished and the generation of gas be interrupted, the gas-drum assumes gradually a lower position until the bent portion of the slip-rod *c'* is forced by its spring against the guide-bracket, so as to release the bolt 40 from the arm or rod *e'*. The spring *J* will then instantly raise the lever *E*, so as to interrupt the generation of gas and prevent any 45 overflow and loss of oil.

By retracting the bolt *q* the lever *E* may be 45 released or moved by hand to simultaneously open or close said valves *f' M H* at will.

The apparatus is operated in the following manner: The oil-tank is filled with oil and compressed air, the latter forcing the oil 50 through the connecting-pipe into the retort, where it is first heated up for starting the apparatus by an alcohol-flame. When the gas-holder is filled with gas the connection of 55 the regulating-lever with the release-rod of the drum is made, the cock of the gas-conducting pipe closed, the cock of the burner-supply pipe opened, and the gas escaping at the burner lighted. The flame of the burner will then 60 keep the retort to its proper heat, and thus continue the generation of vapors. The cock of the conducting-pipe is then opened again,

and the apparatus is ready to generate gas automatically and continuously for any number of burners, according to its capacity. After being once properly started it requires no 65 further attention, as all the different operations are accomplished automatically. It only requires restarting in case the heating-flame is accidentally or intentionally, for cleaning or other purposes, extinguished. 70

I am aware that previous to my present invention the needle-valve, air cut-off, and gas-cock of a gas apparatus in the class of injector mixers had been connected with the gas-holders so as to be operated automatically; but the connections in such case were complicated and did not accomplish the direct actuation of the several valves, as in my arrangement, nor provide for readily and instantaneously actuating them by hand. 75

I do not here claim, broadly, the combination, with the gas-holder drum *R*, of the curved and pivoted slip-rod *c'*, spring *d'*, lever *E*, and the needle-valve *H*, as this will be claimed in another application which I intend to file. 80

Having thus described my invention, I claim as new and desire to secure by Letters Patent—

1. The combination, with the needle-valve *H*, air cut-off *M*, and gas-cock *f'*, of the lever 90 *E* and connections, the spring *J*, and the bolt *q*, for releasing said lever at will from a controlling device.

2. The combination of the needle-valve *H* and cut-off *M*, and gas-cock *f'*, arranged in substantially the same vertical plane, the lever *E*, connected directly to said needle-valve and by links to the lever-arm of said cut-off and cock, the gas-holder drum *R* and connections between said drum and lever, substantially as 100 herein specified.

3. The combination, with the needle-valve *H*, air cut-off *M*, and gas-cock *f'*, of the lever *E* and connections, the spring *J*, the curved and pivoted slip-rod *c'*, the spring *d'*, the gas-holder drum *R*, carrying said slip-rod and connections between said slip-rod and lever *E*, the latter being released by the movement of said slip-rod when said drum falls below a given point, substantially as herein set forth. 110

4. In a gas apparatus, the combination of the vertically-guided drum of the gas-holder, said drum having a pivoted and spring-acted release-rod, with a fulcrumed and spring-acted lever controlling the gas-generating apparatus, said lever having a bolt or other device for being connected to the release-rod of the drum, substantially as described. 115
